UNITED STATES PATENT OFFICE

HENRY P. GROHN, OF SCRANTON, PENNSYLVANIA, ASSIGNOR TO MCCLAVE-BROOKS COMPANY, OF SCRANTON, PENNSYLVANIA, A CORPORATION OF PENNSYLVANIA

DRAW HOOK

Application filed March 19, 1926. Serial No. 96,090.

This invention relates to draw hooks and has for its principal object the provision of a tool that can rapidly be inserted between the links of an endless chain so as to relieve the tension on adjacent transverse members so as to facilitate the withdrawal of a single link.

A further object of the invention lies in the provision of a draw hook particularly suitable for use with endless chain grates.

With endless chains of any kind it frequently happens that a link must be taken out. The usual way of doing this, in chain grates for example, is to shut down the fire, let the grate cool, with a hammer break the link desired to be removed, insert in its place a new link almost invariably of a different type, and then permanently secure this new link in place, frequently by means of a driven pin or a set screw. The draw hook of the present invention provides a very simple means for taking up the slack in a chain without closing down the furnace at all, and while it is for use primarily with chains in which each and every link is independently removable the tool lends itself readily to use with other linked devices. In the particular embodiment shown each link of the chain grate is not only removable but is replaceable but it must be remembered that the invention must not be limited by the illustration except where definitely so required by the claims.

In the drawings:—

Figure 1 is a front elevation of a portion of a chain grate and showing my draw hook in position.

Figure 2 is a side elevation of the draw hook and a portion of the grate.

Figure 3 is a section taken on line 3—3 of Figure 2.

Figure 4 is an elevation of the eccentric.

The main drive shaft 10 of the grate carries a sprocket wheel 11 varying only from usual practice in such details as for example, the enlarged bays 12 and in the provision of an annular flange 14. As shown each of the links of the chain are exactly alike having a flat top portion 16 and two slots 17 and 18 to receive the cylindrical grate rods 20 which

extend in the usual fashion the entire width of the grate. The bays 12 of the sprocket are much wider than usual so that there will be a very appreciable play between the front of any rod and the rear face of the next forward adjacent tooth, so that when the slack is taken up there will be sufficient room in each bay to allow the lowest rod in engagement with the sprocket wheel to move upwardly and rearwardly to give a considerable gap in the chain about the sprocket wheel as the slack in the lower reach of the chain is taken up by the draw hook.

The forward slot 17 of each link extends directly rearwardly from the rod and then downward at an angle of 45°. The rear slot 18 extends from the rod forwardly and downwardly in a curve. By bringing any two adjacent rods 20 together any link engaging both may be removed by first lifting out the rear end of the link, turning the link about the forward rod 20 as a pivot, and then, when it is entirely free of the rear rod 20, removing it without difficulty from the forward rod by moving the link forwardly of the rod when it will free itself by reason of the 45° bevel of the margin of the slot 17.

The main shaft 30 of the draw hook is journaled in lugs 31 each integral with one of the two side pieces 32 of the H-shaped frame 33. The portion of the frame between the two sides 33 may be a mere spacer but I prefer that it shall be as shown at 34, that is integral or integrally secured to the sides or arms 32 and also the lugs 31, so that it forms part of the bearing for the shaft 30. At each side of the frame 33 is an eccentric 35 keyed to the main shaft 30 and serving to position the shaft with respect to the H-shaped frame. The free extending portion of the shaft 30 carries a crank 37 having a socket 38 therein to receive an elongated handle 40.

Each arm 32 of the frame 33 carries an outwardly directed stud 41 about which is pivoted the lower link 43 of a toggle, the upper link 44 of which carries an outwardly extending stud 46 on which the upper end of the lower link 43 is pivoted. Each link 43 is engaged by an eccentric 35 so that as the

handle 40 is turned counterclockwise as in Figure 2 the toggle will be straightened, provided the pin 50 joining the two upper links 44 is held against movement.

- 5 The hook member 51 has a lower pointed end 52 shaped so as to be readily insertible between longitudinally adjacent chain links 15 as shown in Figure 2 and to engage snugly the entire forward end of one link 15c while 10 the straight inner surface 54 of the bar 51 is in engagement with the flat top of the grate chain link. The upper end of this detachable member 51 is hooked as at 55 to receive the pin 50 between the two parallel upper toggle links 44. The hook member 51 is a flat piece of metal and is of such thickness as to slip easily between laterally adjacent links of the chain to be repaired.

One end of each arm 32 of the frame 33 20 is reduced as at 60 so as to fit in between longitudinally adjacent grate chain links and at its extreme end 61 the reduced portion is turned up and curved to engage snugly that portion of the link 15b directly beneath the 25 forward cross bar or rod 20. At the same time the plane portion 64 of each arm of the H-shaped frame rests smoothly on the flat top 16 of the proximate link 15d of the grate.

The method of use of the draw hook is as 30 follows: The machinery for driving the shaft 10 is disconnected temporarily but no other change in the furnace is necessary in order to remove a link. The tool, less the handle 40, the hook 51, and the retaining 35 handspike 70, is placed so that each end 61 will enter in the slot between adjacent grate chain links directly over or a little forward of the shaft 10. The frame 33 is now lowered so that the two parallel flat portions 64 rest 40 upon the next adjacent lower links 15d of the chain and with the crank 37 somewhat to the right of the position shown in Figure 2. The hook 51 is now inserted in the appropriate slot nearly at the bottom of the sprocket 45 wheel 11 and is moved until the flat portion 54 is in contact with the face of the link just above the hook. The pin 50 is now slipped into the hook 55, the spike 70 inserted thru the alined holes in the arms 32 of the frame 50 so as to retain the hook 51 in place, and the crank 37 is moved until the eccentrics 35 seat the pin 50 firmly in place.

The handle 40 is now inserted in the socket of the crank and is moved to the left as seen 55 in Figure 2. This straightens the toggle somewhat but never brings it to a straight line position. The effect of the straightening of the toggle is to bring the end 52 of the hook member 51 and the ends 60 of the members 32 nearer together and this has the effect of bringing the rod 20a into registry with the rear slot 18 of the proximate link which is any one of a row of links 15a to either side of the hook member 51 and the H member or frame 33. By pressing the forward end of

the link to be removed such as 15a toward the axis of the shaft 10 the rear end of the link will be freed. When thus free the link 15a may be moved in the direction of normal movement of the chain, which will then 70 free this link from the other transverse rod 20.

While holding the draw hook in the same position (it will remain in the position to which it is moved without any difficulty since the curve of the eccentric from the point 71 to the point 72 is a true arc struck from the axis of the shaft 30) a new link, preferably exactly like the one taken out, may be inserted; or if the link was removed for inspection only, the link if found satisfactory can be restored to position by first hooking the forward end of the link over one rod, i. e., the forward one, and then turning it into position about this rod as a fulcrum and when it is in proper position with the other rod in the rear socket, releasing the draw hook.

A further reason for the arc 73 between the points 71 and 72 is to prevent the sudden snapping of the handle as might otherwise occur if the draw hook were jarred when in the slack take-up position. Since the toggle is never brought to dead line position, movement of the crank arm 37 will always be followed by a yielding of the toggle until the slack caused by gravity in the lower reach is restored to normal position.

What I claim is:—

1. In a chain tool a relatively stationary member having a chain engaging and holding portion at one end, a member slidable at right angles with respect to said stationary member and having a chain engaging and holding portion, a toggle for causing the 100 slidable member to move with respect to the stationary member to decrease the distance between the two chain engaging portions and means for operating the toggle.

2. In a chain tool a frame having a chain engaging portion at one end, a detachable hook member slidable in the other end and at right angles with respect to the frame, a toggle for causing the hook member to move with respect to the frame, retaining means for preventing the detachable hook member from moving away from the frame and means for straightening the toggle.

3. A chain tool comprising in combination, two cooperating elongated members each having a chain engaging hook at its end, a toggle pivoted to each of said members and having its middle knuckle free, said toggle being bent at the knuckle when said hooks are in extended chain engaging position and means for engaging the middle knuckle to straighten the toggle to cause the hooks to approach each other.

4. In combination, a hooked member having a recess therein, a second hooked mem-

ber slidable in said recess, a pair of links pivoted together and also pivoted to the first hooked member, a pin at the free end of the pair of links, means on the second hooked member to engage said pin to form a toggle of the links, and means to straighten the toggle to cause the second hooked member to slide in said recess.

5. In combination, a frame having a hook at one end and having a pair of parallel arms at the other end, a hook member slidable in the slot between the two parallel arms and having a hook at each end, a hand spike to retain said hook member between said arms, 10 a pair of links pivoted to each other and one of the links being pivoted to the frame, a pin at the free end of the other link to engage one of said hooks, and means to straighten the toggle to cause the pin to move the hook member with respect to the frame.

6. In a draw hook, a frame adapted to rest upon a chain link and to engage an adjacent chain link, a hook member loosely mounted within the frame and adapted to rest upon a 25 third link and to engage the end thereof farthest from the first mentioned link, a toggle pivoted at one end to the frame and freely engaging the hook member at the other end and means for straightening the toggle 30 to cause the hook member to move in the direction of its length.

7. In combination, two elongated members each having a chain engaging hook at its end, a toggle pivoted to each of said members and having its middle knuckle free, means for engaging the middle knuckle to straighten the toggle to cause the hooks to approach each other, and means for engaging the middle knuckle being an eccentric pivoted to one of the elongated members, said eccentric having a true arc for approximately 40 180°, said arc being struck on the greatest radius of the eccentric.

8. An eccentric for operating a toggle at its knuckle which consists of a generally circular disk mounted on a shaft to one side of the approximate center of the disk and in which an appreciable angle of the eccentric measured from its axis of turning is a 45 true arc whereby to minimize the snapping of the toggle by a jar.

9. In a draw hook for removing a detachable link from a chain, a member adapted to engage between two links of the chain, a member slidable in a line generally at right angles to the first member, said second member having a face to engage a third link of the chain and having a hook at one end to engage said third link of the chain, and means 50 for causing the second member to move and carry with it the third link of the chain causing said third link to move in a direction substantially at right angles to the face of the first link which is engaged by the first member.

10. In a draw hook, a frame of generally H-shape, oppositely directed studs extending from the arms of said frame, links pivoted to said studs, a pin, a pair of links each pivoted to said pin, means for pivoting the four links together to form a pair of toggle knuckles and a hook carrying member slid- 55 able in the frame between the studs and loosely engaging the pin to move thereby upon straightening of the toggle.

11. The device of claim 10 in which the means for straightening the toggle is an eccentric carried by the frame and pivoted about an axis passing thru the cross bar of the H-frame.

12. The device of claim 10 in which a readily detachable retaining pin 70 passes thru the ends of both arms of the frame on the same side as the studs 41 to retain the hook member 51 between the arms of the frame, and in which the hook member has a second hook 55 to engage the pin 50 connecting the links 44.

13. A chain tool comprising in combination, a pair of relatively slidable chain hooks, said hooks having chain engaging surfaces which intersect each other at an angle of substantially 90°, a toggle pivoted to each of said hooks, the pivot of one link of said toggle being located on one hook near the point of intersection and the pivot of the other link being located on the other hook so that when the toggle is straight it lies substantially parallel to the chain engaging surface of said other hook, means for exerting force against the knuckle of the toggle whereby said other hook is moved with respect to said one hook, a lever for operating said means, and means for holding the chain hooks so that said right angle between the chain engaging surfaces of the hooks is maintained during the relative motion of the hooks.

14. In combination, two members each having a hook, a toggle pivoted to both members and an eccentric for engaging the central portion of the toggle to straighten it, said eccentric being a true arc thru an angle of more than 90° at its greatest radius.

15. In a draw hook, a frame having an elongated flat surface to engage the substantially horizontal fuel supporting top of a link of a chain as it passes near the top of the sprocket wheel and having an opening or bearing therein, a member slid- 110 able in said opening, said member having an elongated flat surface to engage the substantially vertical fuel supporting top of a second link of the chain grate as said second link is at the side of the sprocket wheel, a hook on one end of the frame and another on one end of the member, the part of the member and the part of the frame between the opening and the hooks forming the respective legs of a right angle, means to move the member substantially vertically upward in the direction 120 130

of a line from the hook to the opening thru which it moves whereby the distance between said hooks is varied without changing the angle between the two legs.

- 5 16. In a draw hook, a frame having an open ended slot, a hook member slidable in said slot, means to move the hook member in a right line direction approximately at right angles to the length of the frame, and detachable means provided for restricting the movement of the hook member in its slot and in which the means for moving the hook member are carried by the frame and loosely engage the far end of the hook member.
- 15 17. A link remover comprising a frame member and a hook member adapted to engage the links of a chain only at the point where the chain is bent over a sprocket in which position the fuel supporting surfaces 20 of the links engaged are substantially at right angles to each other, means for preventing movement between the frame member and its engaged link, and means carried by the frame member at the end distant from said last 25 mentioned means for preventing movement between the hook member and the link which it engages, means for moving the hook member in a direction toward and at right angles to the fuel supporting surface of the link held 30 by the frame member whereby the engaged links are drawn toward each other to release the tension on links adjacent the engaged links so that the tension released links may be removed at will for inspection or 35 renewal.

18. A link remover as defined in claim 17, said means for moving the hook member comprising a toggle.

19. A link remover as defined in claim 17, 40 said means for moving the hook member comprising a toggle having one link pivoted to said frame member and the other link pivoted on said hook member, and a lever pivoted to one of said chain link engaging members for 45 operating the toggle.

20. A tool comprising a bar adapted to rest upon the fuel supporting surface of a link of a chain grate as such link approaches the top of the sprocket wheel of the grate, a hook on the end of the bar to engage the forward end of said link, a cooperating member slidably mounted with respect to said bar and having surfaces to engage the fuel supporting top and the rear end of a link 50 located lower upon the sprocket wheel than the first mentioned link, and means for actuating said cooperating member to cause the member and the link engaged thereby to move upwardly, moving such link in the 55 direction of movement of the sprocket wheel and therefore closer to said first link, whereby a third link located laterally adjacent the first and second links may be removed or replaced.

- 65 21. In a tool for removing links from a

chain grate, the combination of two bars each having a chain engaging hook at one end and each having a flat link engaging surface, of means for causing one of the bars to move at right angles to the link engaging surface of the other bar. 70

22. In combination, a frame adapted to engage the fuel supporting surface of a link of a chain grate, a member adapted to engage the far end of a second link of said grate, and means carried by said frame to cause the member to slide in the direction of its length whereby to cause said links to approach one another so that a third link can be removed from said grate. 75

23. In a chain grate draw hook, a frame to engage the substantially horizontal top and the forward end of a link of a chain grate, a member adapted to engage the top and the rear end of a second link, and means to cause 80 the member and the second link to slide at right angles to the top of the first link. 85

24. The device of claim 20 in which the actuating means consists of a toggle and an eccentric pressing against the knuckle of the toggle, said eccentric having a surface which is a true arc thru an angle greater than 60° at its greatest radius whereby the cooperating member will be locked in position to permit the replacement of the third link whenever the eccentric is substantially at its mid-position of greatest radius, said toggle being substantially straight in such position and a movement of 30° to either side of mid-position causing no movement of the toggle. 90

In testimony whereof I affix my signature.
